Lacey & Lacey, Attorneys

UNITED STATES PATENT OFFICE.

WALTER ECKERT, OF OSGOOD, INDIANA.

DISPLAY RACK.

Application filed January 6, 1925. Serial No. 912.

My invention is a display rack designed especially for the display of sample doors, whether the doors be screen doors or doors of any other type. The object of the invention is to provide a simple, inexpensive and compact device by the use of which a plurality of doors may be supported in upright position within a small space so that they may be readily examined by prospective customers without one door interfering with an inspection of another door although the doors will be arranged close together. The invention seeks to provide a door displaying rack in which the sample doors may be easily secured in the rack and the rack may be readily adjusted to the size of the door. The invention is illustrated in the accompanying drawing and will be hereinafter fully set forth.

20 In the drawing:

Figure 1 is a side elevation of one embodiment of my invention with a screen door mounted therein;

Fig. 2 is a plan view of the same, and

25 Fig. 3 is an enlarged detail section on the line 3—3 of Fig. 2.

In carrying out my invention, I employ a post or standard 1 which will ordinarily be of a height to accommodate standard doors 30 of maximum height. This standard is illustrated as a wooden bar or timber, but it will be understood that the standard may be constructed of channel iron or other material. I also provide a substantially triangular base plate 2 and a similar cap plate 3 which are secured to the bottom and top ends of the post, respectively. The plates 2 and 3 are notched or recessed at their apexes so as to fit around the post and they are rigidly connected with the post by angle brackets 4 secured to the sides of the post and to the top of the base plate 2 and the under side of the cap plate 3. If so desired, screws, indicated at 5, may be also inserted through the 40 post into the edge of the base and cap plates so as to further secure the parts together. The brackets 4 supporting the cap plate may obviously be set at any desired point of the post or standard below the extreme upper 45 end of the latter, and the device may thus be easily adjusted to the height of the doors to be displayed. The rack is, of course, supplied in a number of standard sizes but it may sometimes happen that the only racks 50 available are longer than the doors intended to be displayed therein, and by adjusting the

cap plate vertically the delay of waiting for a smaller size rack is avoided. A plurality of pins 6 are secured in the base plate 2 adjacent and parallel with the basal edge 60 of the same, and these pins project above the base plate a sufficient distance to serve as pivots for the doors, indicated at 7, to be displayed. The pins will be spaced apart equidistantly and at such intervals that the doors 65 may swing freely and any one door may be left projecting from the rack, as shown in Fig. 2, while the other doors may be swung aside so as to fold close to each other and to the rack. The customer is thus enabled to 70 inspect any one door or all the doors as completely as though only one door was displayed. Sockets, such as indicated at 8, are formed in the upper and lower ends of the doors to be fitted in the racks and the socket 75 in the lower end of the door is, of course, engaged pivotally over the upper projecting end of a pin 6. A plurality of countersunk 80 openings 9 are formed through the cap plate 3 adjacent the basal edge thereof and parallel 85 with said edge and also aligned vertically with the respective pins 6. Headed pins 10 are engaged in these countersunk openings 9 to engage the respectively subjacent sockets 8 in the upper ends of the displayed 90 doors, it being readily noted that the heads of the pins will engage within the countersink of the openings so as to prevent the pins dropping entirely through the openings and also preventing their loss when a door is not 95 engaged thereby. The countersink of the several openings 9 will be of such depth that the head of the pin engaged therein will be flush with or below the top surface of the cap plate, and a latch bar 11 is pivoted between its ends, as indicated at 12, upon the cap plate in such position that it may extend over the heads of all the pins 10 and thereby prevent them being accidentally pushed upward and releasing a door. If the latch bar 100 be turned to a position parallel with the basal edge of the triangular cap plate, as indicated by full lines in Fig. 2, it will obviously extend over the heads of all the pins 10 and over the openings receiving said pins. 105 If the latch bar be swung pivotally to the position shown in dotted lines, the pins will obviously be exposed and any pin may be withdrawn so as to release a door held thereby. In placing a door in the rack, the door 110 may be first engaged over the lower pin 6 and then easily brought into position under

the cap plate, after which a pin 10 is engaged with the socket 8 in the upper end of the door to retain it in display position.

My device is obviously exceedingly simple in construction and will occupy but small space when set up for use. By its use, a large number of screen doors or other doors may be displayed so that they may be easily and fully inspected without requiring laborious handling of the same by the salesman.

The device may be set up at such point in a storeroom as will prove most convenient, and a bracket 13 is secured upon one side of the post to facilitate the attachment of the rack to a counter or to a wall so that it will be held firmly in its upright position. This bracket 13 may be of any desired or approved form.

Having thus described the invention, I claim:

1. A display rack comprising a support, upper and lower members projected laterally from the support in the same direction in parallel relation, the upper member having a plurality of openings extending vertically therethrough, pivots secured to and projecting vertically from the lower member and disposed in coincident position with the respective vertical openings of the upper member, and pivots removably fitted in the openings of the upper member and acting jointly with the lower pivots to engage sockets in

the upper and lower edges of the articles to be displayed.

2. A display rack for doors and like articles having sockets in their upper and lower edges, the same consisting of a post, upper and lower members projected laterally from the post in the same direction, the upper member having a plurality of openings extending vertically therethrough, pivots projected upwardly from the lower member in coincident position with the openings of the upper member, headed pivots removably fitted in the openings of the upper member and acting jointly with the lower pivots to pivotally and detachably support the articles to be displayed by engaging the sockets in the edges thereof.

3. A display rack for doors having sockets in their upper and lower edges, the same comprising a post, a cap and base plates secured to the post and having vertical openings in coincident position, pivots secured in the openings of the base plate and extended upwardly therefrom, headed pivots removably fitted in the openings of the cap plate and depending therefrom, and a latch on the cap plate to extend over the removable pivots and prevent displacement thereof.

In testimony whereof I affix my signature.

WALTER ECKERT. [L. S.]
